HYDROCARBON OIL TREATMENT

Seymour W. Ferris, Aldan, Pa., assignor to The
Atlantic Refining Company, Philadelphia, Pa.,
a corporation of Pennsylvania

Application July 18, 1935, Serial No. 31,966

7 Claims. (Cl. 196—13)

The present invention relates to a process for obtaining continuous and preferably continuous countercurrent contact between partially immiscible liquids, and relates more particularly to the extraction of components from hydrocarbon oils with a solvent or solvent mixture which will selectively dissolve such components.

An object of this invention is the extraction of components of hydrocarbon oils, especially naphthenic and color-imparting bodies, in such a manner that the extracted components will comprise a minor portion of the oil undergoing treatment, and the separation of such extracted components from the refined oil will be relatively rapid and complete.

A further object of this invention is the extraction of components of hydrocarbon oils with the minimum quantity of a selective solvent which will effect the desired extraction at temperatures such that the application of heat and/or refrigeration will be substantially reduced.

Heretofore, it has been found that certain selective solvents, as for example, nitrobenzene, phenol, aniline, furfural and others, may be employed to effect a separation of hydrocarbon oils, such as petroleum, or distillates or residuum thereof, into fractions of substantially the same boiling range but of different chemical composition and of different physical properties. The difference in physical properties of the fractions so produced, i. e., the degree of paraffinic or naphthenic of said fractions, may be expressed by the relationship of viscosity to gravity for any particular oil. The viscosity-gravity constant, as developed by Hill and Coats, referred to in Industrial and Engineering Chemistry, vol. 20, page 641 (1928) will be used herein to indicate the degree of paraffinic or naphthenic of the oil fractions; the lower the value for the constant, the higher the degree of paraffinity of the oil.

In the solvent extraction of certain lubricating oil stocks, particularly highly viscous and relatively expensive stock such as, for example, Pennsylvania cylinder stock, it is desirable to remove a relatively small fraction, i. e., of the order of 5% to 10%, as extract, concentrating therein as much of the naphthenic hydrocarbons and color-bodies as is possible. When this is effected, for example, my means of a solvent having great solvent power, such as nitrobenzene or phenol, the quantity of solvent employed is relatively small and the rate of settling and

separation of the raffinate and extract phases is undesirably slow.

In the case of extraction with a relatively large volume of solvent, for example, 150% to 300% by volume of the stock, the extract phase is present in considerably larger volume than is the raffinate phase and constitutes the continuous phase, therefore the raffinate phase or disperse phase is, in all probability, distributed in droplets and settles through the relatively non-viscous extract phase. In the case of extraction with a small volume of solvent, for example, the extraction of a Pennsylvania cylinder stock with 20% to 70% by volume of solvent, there is considerably more of the raffinate phase present than the extract phase, therefore, the extract phase is probably distributed as droplets and must settle through the viscous raffinate phase. In this instance, settling is much more difficult and lengthy than in the former case.

I therefore propose to enhance the settling rates in the extraction of stocks such as may be obtained from Pennsylvania crude oil, as well as oil stocks derived from crudes other than Pennsylvania, by artificially increasing the proportion of extract phase in the mixture resulting from the contacting of the oil stock with solvent to such a degree that the extract phase will always constitute the continuous phase of the system. This I accomplish without employing additional solvent and without substantially changing the various other conditions of the extraction process. For example, in a continuous batch extraction, 100 parts by volume of stock and 50 parts by volume of solvent are charged continuously to a mixing vessel and the resulting mixture is passed to a settling vessel wherein in the raffinate and extract phases are permitted to separate. Normally, both the raffinate phase and the extract phase would be withdrawn continuously from the settling vessel at a rate corresponding to the rate of charge to the mixing vessel and both phases would be removed from the system. However, in accordance with my invention, a portion of the extract phase withdrawn from the settling vessel, for example, from a few percent up to as much as 80% or 90%, is returned to the mixing vessel and is preferably agitated with the stock and solvents normally charged thereto. In this manner, without employing additional quantities of solvent and without substantially changing the composition equilibrium between the raffinate and extract phases, the volume percentage of extract in the mixture passing from the mix-

ing vessel to the settling vessel is suitably increased and the settling rate and completeness of separation is markedly enhanced.

The effect of increasing the volume ratio of extract phase above that which is normally encountered in extractions involving the use of relatively small quantities of solvent, for example, of the order of 50% by volume of the stock, may be seen from the following tables. The various oil stocks were batch extracted, the raffinate and extract phases were separated and, without change of temperature, the extract phase was then admixed in various proportions with the raffinate phase and settled. The effect of varying the volume of extract phase to raffinate phase was noted, particularly with respect to settling rates of the phases.

From the data given in Tables I and II, it will be seen that, in general, when the volume ratio of extract phase to raffinate phase is of the order of 0.4 or greater, the rate of separation of the phases and the settling into layers is much greater than in the instances where such ratio is less than about 0.4. In practice this ratio will vary, depending upon the character of the solvent and stock, the quantity of solvent employed and the temperature of separation.

Referring now to Fig. 1 of the accompanying drawings, which illustrates graphically the relationship between settling time of the phases and the volume percent of solvent employed when a Pennsylvania residuum is extracted with nitrobenzene and settled at 82° F., it will be noted that for treatments with from about 40% to about

75

56% by volume of solvent based on the stock, the settling time was of the order of 1000 seconds, but with about 56% or more of solvent, the settling time was of the order of about 150 seconds. 5 In other words, when employing less than about 56% by volume of solvent, under these particular conditions, the ratio of extract phase to raffinate phase is such that the viscous raffinate constitutes the continuous phase through which the 10 relatively non-viscous extract or disperse phase must settle, with the resultant slow rate of stratification. On the other hand, when 56% to 60% or more of solvent is employed, the relationship of the phases appears to be reversed, i. e., the 15 non-viscous extract constitutes the continuous phase, and the viscous raffinate the disperse phase. When this relationship exists, settling and stratification of the extract and raffinate phases into layers occurs relatively rapidly.

20 The shift in phase relationships as correlated with the rate of settling and formation of extract and raffinate layers is further illustrated in Figures 2, 3, and 4 of the drawings.

25 A residual stock having a Saybolt Universal viscosity of 194 seconds at 210° F., an A. P. I. gravity of 22.3° at 60° F., and a viscosity-gravity constant of 0.836 was admixed with 50% by volume of nitrobenzene and permitted to settle at 820° F. It was found that settling was substantially complete after about 700 seconds and the ratio of the volume of extract layer to raffinate layer was 0.356. This relationship of extract to raffinate as correlated with settling time is represented by the upper end of the curve of Fig. 2, 30 and it will be seen that the settling rate is of the order of 700 seconds. Under the conditions of this separation, with an extract-raffinate ratio of 0.356, the light colored, viscous raffinate constituted the continuous phase throughout which 35 was dispersed the dark colored, relatively non-viscous extract phase. This condition is clearly shown by the photomicrograph Fig. 3, taken during the settling step.

40 After separating the resultant extract and raffinate layers, the extract and raffinate were admixed in varying proportions so that the ratio of extract to raffinate was successively increased above the value 0.356, while the temperature and composition equilibrium was maintained unchanged. The settling time for the various mixtures was determined and it will be seen from the curve of Fig. 2 that when the volume ratio of extract to raffinate phases was of the order of about 0.47 or greater, the rate of settling was markedly increased, i. e., to the order of about 200 seconds. The photomicrograph Fig. 4, taken during the settling step in which the ratio of extract phase to raffinate phase was 1.0, shows that the phase relationship has been reversed. 45 In this case the dark colored, relatively non-viscous extract constitutes the continuous phase, while the light colored, viscous raffinate constitutes the disperse phase, and settling of the raffinate through the extract is relatively rapid. In both instances the composition of the extract and raffinate phases is identical, since at constant temperature the equilibrium between the two phases is undisturbed even though the ratio of extract phase to raffinate phase in one case is 0.356 and in the second, 1.0. Thus, it appears that in the solvent extraction of oils, employing relatively small quantities of solvent, it becomes necessary to adjust the ratio of extract to raffinate, and therefore the phase relationship, in such

5 a manner that rapid and complete settling of the phases may be accomplished.

For purposes of illustration, reference is made to Fig. 5 of the accompanying drawings which shows diagrammatically, one form of apparatus 10 suitable for carrying on my process:

In the drawings, a series of alternate mixing vessels 6, 11 and 16 and settling vessels 8, 14 and 19 are disposed in step-like arrangement, the mixing vessels being provided with paddle stirrers 7, 12 and 17 respectively, or other suitable mixing devices, means for introducing thereinto oil and solvent, and means for passing the mixture therefrom into the respective settling vessels. The settling vessels are provided with heating and/or cooling coils 9, 9' and 9'' and means for passing undissolved oil (raffinate) to succeeding stages, and solvent containing dissolved oil (extract) to the mixing vessel of the stage from which it was withdrawn and/or to the mixing 15 vessels of the preceding stages. The system is equipped with low pressure pumps, feed lines and heat exchangers so arranged as to maintain a regulated countercurrent flow of oil and solvent through the extraction stages, the heat exchangers 20 25 4, 24, 30, 33, 39, 42 and 49 controlling the temperature of the oil and solvent streams, and indirectly the temperatures in the mixing and settling vessels.

In the operation of my process, I may choose, 30 for example, to extract a Pennsylvania lubricating oil distillate having a Saybolt Universal viscosity of 143 seconds at 210° F., an A. P. I. gravity of 26.5°, a viscosity-gravity constant of 0.810, and an O. D. color of 2929, employing nitroben- 35 zene as the selective solvent.

In order to commence the operation of the extraction system, 100 barrels per hour, for example, of the above mentioned oil stock, supplied from a storage vessel not shown, is drawn through valve-controlled pipe 1 by means of pump 2, and is passed through pipe 3 and heat exchanger 4 wherein it is brought to the desired temperature, for example, 70° F. The oil is then passed by means of pipe 5 into mixing vessel 6. 40 The selective solvent, i. e., nitrobenzene, is conducted, at a rate of, for example, 150 barrels per hour, from a storage vessel not shown, through valve-controlled pipe 21, and is passed by means of pump 22 through pipe 23 and heat exchanger 24 wherein it is brought to the desired temperature, for example, 70° F. The solvent is then passed through pipe 25 into mixing vessel 16. 45 After sufficient oil stock and solvent have been supplied to the system, a countercurrent flow will be set up and the extraction process will commence to function. When equilibrium under these operating conditions is reached and the proper flow of raffinate and extract is established, the volume of nitrobenzene charged to the system is reduced from 150 barrels per hour to about 40 barrels per hour, in order that the extraction 50 may be carried on with a relatively small volume of solvent. The rate of charge of oil stock is, however, maintained constant at about 100 barrels per hour.

55 The oil stock is charged to the mixing vessel 6, and a portion of the partially spent solvent (extract) from the bottom of settling vessel 14, which flows through valve-controlled pipe 35, is forced by pump 36 through pipe 37 and valve-controlled pipe 41 to heat exchanger 42, wherein the temperature of the extract is adjusted to about 70° F. This extract is passed from heat exchanger 42 through pipe 43 into mixing vessel 75

6, wherein it is contacted with the oil stock by
agitation with stirrer 7. The oil-solvent mixture
is withdrawn from vessel 6 by means of pipe 9
and is passed into settling vessel 8 wherein set-
tling and separation of the raffinate and extract
phases is effected at a temperature of about 70°
F., the raffinate comprising the upper layer and
the extract the lower layer. The lower or extract
layer is withdrawn from the bottom of settling
vessel 8 by means of valve-controlled pipe 44
and a portion of such extract is forced from the
system by pump 45, through pipe 46 and valve-
controlled pipe 47, and the extract may there-
after be separated into oil and solvent fractions
by distillation. The remaining portion of ex-
tract, for example, 100 barrels per hour or 100%
based on the volume of oil stock charged, is
passed from pipe 46 through pipe 48, heat ex-
changer 49 and valve-controlled pipe 50 into
mixing vessel 6. This operation occurs simul-
taneously with the normal mixing step and con-
stitutes the recirculation of extract to the same
stage of the system from which it was with-
drawn, and such operation makes possible the
employment of small quantities of solvent while
still maintaining a rapid settling rate.

The undissolved oil layer or raffinate, con-
taining a small quantity of solvent, occupies the
upper portion of settling vessel 8, and is passed
therefrom by means of pipe 10 into the mixing
vessel 11 of the 2nd stage. Vessel 11 is sim-
ultaneously supplied with a portion of the par-
tially spent solvent (extract) from the lower
section of settling vessel 19, which extract flows
through valve-controlled pipe 26 and is forced
by pump 27 through pipe 28 and valve-controlled
pipe 32 into heat exchanger 33, wherein the
temperature of the extract is adjusted to about
70° F., and thence through pipe 34 into said
mixing vessel 11. The oil and solvent are here-
in thoroughly contacted by means of stirrer 12
and the oil-solvent mixture is passed by means
of pipe 13 into settling vessel 14 wherein settling
and separation of the extract and raffinate phases
is effected at a temperature of about 70° F.,
the raffinate comprising the upper layer and the
extract the lower layer. This lower or extract
layer is withdrawn from the bottom of settling
vessel 14 by means of valve-controlled pipe 35
and a portion thereof is pumped to the 1st stage
mixing vessel as above described. The remain-
ing portion, for example, 60 barrels per hour or
60% based on the volume of the oil stock charged,
is passed from pipe 37 through pipe 38, heat ex-
changer 39 and valve-controlled pipe 40 into mix-
ing vessel 11. This step of recirculating occurs
simultaneously with the normal mixing step, and,
as above pointed out, permits of a rapid rate of
settling and formation of extract and raffinate
layers, particularly when relatively small quan-
tities of solvent are employed.

The undissolved oil layer or raffinate, contain-
ing a small quantity of solvent, occupies the up-
per portion of settling vessel 14, and is passed
therefrom by means of pipe 15 into mixing ves-
sel 16 of the 3rd stage. Vessel 16 is sim-
ultaneously supplied with fresh solvent which is in-
troduced thereinto from a storage vessel not
shown. Such solvent is drawn through valve-
controlled pipes 21 and is forced by pump 22
through pipe 23, the temperature being adjusted
in heat exchanger 24 to about 70° F. and thence
passed by means of pipe 25 into mixing vessel 16.
The oil and solvent are herein thoroughly con-
tacted by means of stirrer 17 and the oil-solvent

mixture is passed through pipe 18 into settling
vessel 19 wherein settling and separation of the
extract and raffinate phases is effected at a tem-
perature of about 70° F., the raffinate comprising
the upper layer and the extract the lower
layer. This lower or extract layer is withdrawn
from the bottom of settling vessel 19 by means
of valve-controlled pipe 26 and a portion thereof
is pumped to the 2nd stage mixing vessel 11 as
hereinbefore described. The remaining portion,
for example, 60 barrels per hour or 60% based
on the volume of the oil stock charged, is passed
from pipe 28 through pipe 29, heat exchanger
30 and valve-controlled pipe 31 into mixing ves-
sel 16. Here again the step of recirculating oc-
curs simultaneously with the normal mixing step
and permits of relatively rapid settling and for-
mation of extract and raffinate layers. The un-
dissolved oil layer or raffinate, containing a small
quantity of solvent, is withdrawn from the upper
portion of settling vessel 19 by means of valve-
controlled pipe 20. The residual solvent may be
removed from the raffinate by distillation, pref-
erably under reduced pressure.

In accordance with the above described op-
eration of the extraction system, employing re-
circulation of extract to each stage, there was
produced a raffinate oil amounting to 94.3% of
the stock charged, such raffinate having a Say-
bolt Universal viscosity of 127 seconds at 210° F.,
an A. P. I. gravity of 27.1° at 60° F., a viscosity-
gravity constant of 0.806 and an O. D. color of
1700. The extract oil, amounting to 5.7% of
the stock charged, had a Saybolt Universal vis-
cosity of 360 seconds at 210° F., an A. P. I. grav-
ity of 14.0° at 60° F. and a viscosity-gravity
constant of 0.895.

While, in the example given above, I have
shown a 3-stage countercurrent system, I do not
intend to limit myself thereto, but may employ
any system of one or more stages, all of the stages
being operated at the same or different tempera-
tures. Furthermore, while I have shown recircula-
tion of extract to each of the stages of the sys-
tem, I have found that in some instances it is
necessary or desirable to recirculate extract to
only one of the stages, usually the 1st stage, in
order to effect a rapid settling and formation of
extract and raffinate layers. It will be seen that
in a multi-stage extraction system, the ratio of
solvent or extract to raffinate in the last stage is
greatest, and, in general, becomes progressively
less in the successive preceding stages, so that in
the 1st or possibly the 1st and 2nd stages the
ratio of extract to raffinate may be so low that
satisfactory settling cannot be obtained. In such
instances, the application of recirculation to the
1st and/or 2nd stages becomes absolutely neces-
sary in order that the system may function suc-
cessfully. In all cases, regardless of the number
of stages employed and the particular stages to
which recirculation is applied, it is to be noted
that for any given stage the composition equilib-
rium between extract and raffinate phases is sub-
stantially unchanged by the addition or recircu-
lation of extract, since the extract recirculated
was in equilibrium with the raffinate during
settling.

The following example will serve as a further
illustration of the results which may be obtained
in accordance with my invention.

A Pennsylvania residuum having a Saybolt
Universal viscosity of 162 seconds at 210° F., an
A. P. I. gravity of 25° at 60° F., a viscosity-gravity
constant of 0.818 and an O. D. color of 8220 was 75

charged to a 5-stage continuous countercurrent extraction system at a rate of 200 barrels per hour. The selective solvent, in this instance, nitro-benzene, was charged to the system at the 5 rate of 140 barrels per hour. The extraction was carried out continuously while maintaining a uniform temperature of about 70° F. in each stage, and a portion of the extract withdrawn from each stage was recirculated to each respective stage at the rate of about 400 barrels per hour. The raffinate oil obtained from the system, after removal therefrom of traces of solvent, amounted to about 94% by volume of the stock charged. This oil had a Saybolt Universal viscosity of 147 seconds at 210° F., and an A. P. I. 10 gravity of 26.5° at 60° F., a viscosity-gravity constant of 0.808 and an O. D. color of 4215. The extract oil, after removal of solvent, amounted to about 6% by volume of the stock charged and 15 had a Saybolt Universal viscosity of 610 seconds at 210°, an A. P. I. gravity of 12.8° at 60° F., a viscosity-gravity constant of 0.902 and an O. D. color of 33,243.

My invention is particularly adapted to the extraction of hydrocarbon oils, especially oils derived from Pennsylvania crudes, when it is necessary to use relatively small quantities of solvent. In the solvent treatment of Pennsylvania lubricating stocks, one of the primary requirements 25 is the production of high yields of raffinate of the desired quality, since such lubricating stocks are relatively expensive. In order to obtain high yields of raffinate oil when employing selective solvents of high selectivity and solvent power, it becomes necessary to use small quantities of 30 solvent to prevent too great an extraction of desirable oil components along with the undesirable components which are to be extracted. Since the use of relatively small quantities of solvent, i. e., 35 of the order of 20% to 70% of the volume of the stock, involves certain difficulties with respect to settling of the extract from the raffinate phase, which difficulties at times render the extraction inoperable, it becomes necessary to resort to the 40 recirculation of extract to effect the settling at reasonably rapid rates. For example, a Pennsylvania lubricating stock, when extracted in the normal manner with 40% by volume of nitrobenzene, could not be satisfactorily settled within 45 in a practical and reasonable time. However, by artificially increasing the ratio of extract phase to raffinate phase, in accordance with my invention, the settling rate was markedly increased and the extraction was completed successfully 50 to give a yield of over 90% of raffinate oil of desired quality. On the other hand, when the same lubricating stock was extracted with 100% by volume of nitrobenzene, no separation difficulties were encountered, but there resulted a 55 yield of only 84% of raffinate oil which was of a higher quality than that desired.

In the extraction of wax-bearing hydrocarbon oils, the waxy hydrocarbons usually remain in the more paraffinic or raffinate layer. Such 60 layer may be separated into solid and liquid hydrocarbons by any of the well-known dewaxing processes, such as by cold settling, centrifuging or filter pressing. In many instances it may be advantageous to dewax the oil prior to subjecting same to extraction. However, it is to be understood that in accordance with my invention, dewaxing may be effected either prior or subsequent to extraction. Furthermore, the oil stocks employed may be subjected to any desired 65 refining treatment, for example, acid treatment,

prior to extraction, or the oil fractions resulting from my extraction process may be further refined in the conventional manner with acid and/or clay or other treatment.

My process is practically independent of the 5 particular nature or source of the crude oil fractions to be extracted. However, my process is especially adapted to the treatment of viscous hydrocarbon oils, whether they be distillate oils or residuums and particularly when normal 10 settling periods of the order of 5,000 to 10,000 seconds or greater are encountered. Herein, while I have shown the use of selective solvents such as nitrobenzene, dichloro ethyl ether and phenol, I do not intend to limit myself thereto 15 but contemplate as within the scope of my invention any one or more of the conventional selective solvents, including, for example, any one or mixture of those mentioned by Ferris, Birkhimer and Henderson in their article in Industrial and Engineering Chemistry, vol. 23, p. 20 753 etc. (1931).

Herein, and in the appended claims, when oil is specifically referred to as being "viscous", it is to be understood that the oil is of substantial 25 viscosity, i. e., of the order of 50 seconds Saybolt Universal at 100° F., or more.

What I claim is:

1. In a process for extracting a viscous hydrocarbon oil with a selective solvent in an extraction system comprising a mixing zone and a settling zone to form a raffinate phase containing the more paraffinic constituents of the oil and an extract phase containing the more naphthenic constituents thereof, wherein the quantity of selective solvent employed is of the order of from 20% to 70% by volume of the viscous hydrocarbon oil being treated and causes the raffinate phase to form the continuous phase and the extract phase to form the disperse phase, the step of reversing the phase relationship between raffinate and extract phases to enhance the rate of separation of one from the other in said settling zone, which comprises intimately commingling the admixture of raffinate and extract phases in said mixing zone with such additional quantity of extract phase as will cause a reversal of said phase relationship, said added extract phase having substantially the same composition as the extract phase being separated in 50 said settling zone.

2. In a process of extracting a viscous hydrocarbon oil of Pennsylvania type with nitrobenzene in an extraction system comprising a mixing zone and a settling zone to form a raffinate phase containing the more paraffinic constituents of the oil and an extract phase containing the more naphthenic constituents thereof, wherein the quantity of nitrobenzene employed is of the order of from 20% to 70% by volume of the viscous hydrocarbon oil being treated and causes the raffinate phase to form the continuous phase and the extract phase to form the disperse phase, the step of reversing the phase relationship between raffinate and extract phases to enhance the rate of separation of one from the other in said settling zone, which comprises intimately commingling the admixture of raffinate and extract phases in said mixing zone 70 with such additional quantity of extract phase as will cause a reversal of said phase relationship, said added extract phase having substantially the same composition as the extract phase being separated in said settling zone.

3. The process as recited in claim 1, wherein the selective solvent employed is nitrobenzene.
4. In a process for extracting a viscous hydrocarbon oil with a selective solvent in an extraction system comprising a mixing zone and a settling zone to form a raffinate phase containing the more paraffinic constituents of the oil and an extract phase containing the more naphthenic constituents thereof, wherein the volume ratio of the extract phase to the raffinate phase is less than substantially 0.4, said extract phase comprising the disperse phase and said raffinate phase comprising the continuous phase, the step of increasing the volume ratio of extract phase to raffinate phase to a value greater than substantially 0.4 to cause reversal of the phase relationship between the extract and the raffinate phases and to enhance the rate of separation of one from the other in said settling zone, which comprises intimately commingling the admixture of extract and raffinate phase in said mixing zone with such additional quantity of extract phase as will increase said ratio to a value greater than substantially 0.4, said added extract phase having substantially the same composition as the extract phase being separated in said settling zone.
5. The process as received in claim 4, wherein the quantity of selective solvent employed in extracting the viscous hydrocarbon oil is of the order from 20% to 70% by volume of the viscous hydrocarbon oil being treated.
6. The process as recited in claim 4 wherein the selective solvent employed is nitrobenzene.
7. In a process for extracting a viscous hydrocarbon oil of Pennsylvania type with nitrobenzene in an extractive system comprising a mixing zone and a settling zone to form a raffinate phase containing the more paraffinic constituents of the oil and an extract phase containing the more naphthenic constituents thereof, wherein the volume ratio of the extract phase to the raffinate phase is less than substantially 0.4, said extract phase comprising the disperse phase and said raffinate phase comprising the continuous phase, the step of increasing the volume ratio of extract phase to raffinate phase to a value greater than substantially 0.4 to cause reversal of the phase relationship between the extract and the raffinate phases and to enhance the rate of separation of one from the other in said settling zone, which comprises intimately commingling the admixture of extract and raffinate phases in said mixing zone with such additional quantity of extract phase as will increase said ratio to a value greater than substantially 0.4, said added extract phase having substantially the same composition as the extract phase being separated in said settling zone.

SEYMOUR W. FERRIS. 30

CERTIFICATE OF CORRECTION.

Patent No. 2,151,592.

March 21, 1939.

SEYMOUR W. FERRIS.

It is hereby certified that error appears in the printed specification of the above numbered patent requiring correction as follows: Page 1, first column, line 39, for "of" second occurrence, read or; line 52, for "my" read by; page 3, first column, line 29, for "820° F." read 82° F.; page 4, first column, line 70, for "pipes" read pipe; page 4, second column, line 49, for "reaffinite" read raffinate; page 5, first column, line 21, for "210°" read 210° F.; line 66, for "an" read any; page 6, first column, line 9, claim 4, for "constituents" read constituents; line 21, same claim, for "phase" read phases; line 28, claim 5, for "received" read recited; and second column, line 1, same claim, before "from" insert of; line 7, claim 7, for "extractive" read extraction; and that the said Letters Patent should be read with this correction therein that the same may conform to the record of the case in the Patent Office.

Signed and sealed this 2nd day of May, A. D. 1939.

Henry Van Arsdale
